[57] CLAIM

The ornamental design for an ash tray lid for waste receptacle, as shown and described.

DESCRIPTION

FIG. 1 is a perspective view of an ash tray lid for waste receptacle embodying my new design.

FIG. 2 is a side elevational view thereof on an enlarged scale, the opposite side, and rear being mirror images; FIG. 3 is a top plan view thereof on an enlarged scale; FIG. 4 is a bottom plan view thereof on an enlarged scale;

FIG. 5 is a cross-sectional view thereof on an enlarged scale as taken along line 5—5 of FIG. 3.
